(57) **CLAIM**

The ornamental design for a handheld meter, as shown and described.

DESCRIPTION

FIG. 1 is an exploded perspective view of the ornamental design for a handheld meter, shown with the main body of the meter and the battery compartment portion separated. FIG. 2 is a front view of the handheld meter, shown in a fully assembled state.

FIG. 3 is a back (or rear) view of the handheld meter, shown in a fully assembled state.

FIG. 4 is a left side view of the handheld meter, shown in a fully assembled state.

FIG. 5 is a right side view of the handheld meter, shown in a fully assembled state.

FIG. 6 is a top view of the handheld meter, shown in a fully assembled state.

FIG. 7 is a bottom view of the handheld meter, shown in a fully assembled state.

FIG. 8 is a front view of the battery compartment portion of the handheld meter, shown in isolation for clarity of disclosure.

FIG. 9 is a back (or rear) view of the battery compartment portion of the handheld meter, shown in isolation for clarity of disclosure.

FIG. 10 is a left side view of the battery compartment portion of the handheld meter, shown in isolation for clarity of disclosure.

FIG. 11 is a right side view of the battery compartment portion of the handheld meter, shown in isolation for clarity of disclosure.

FIG. 12 is a top view of the battery compartment portion of the handheld meter, shown in isolation for clarity of disclosure; and,

FIG. 13 is a bottom view of the battery compartment portion of the handheld meter, shown in isolation for clarity of disclosure.

(Continued)

The portion of the handheld meter shown in broken lines forms no part of the claimed design.
